UNITED STATES PATENT OFFICE.

GEORGE HANN AND ANTON THOMA, OF THREE RIVERS, MICHIGAN.

WIRE-STRETCHING MACHINE.

SPECIFICATION forming part of Letters Patent No. 355,014, dated December 28, 1886.

Application filed July 7, 1885. Serial No. 170,871. (Model.)

To all whom it may concern:

Be it known that we, GEORGE HANN and ANTON THOMA, both citizens of the United States, and residents of Three Rivers, St. Joseph county, Michigan, have invented a new, useful, and valuable Improvement in Wire-Stretching Machines; and we do hereby declare that the following is a full, clear, and exact description of the construction and operation 10 of the same, as will be seen from the accompanying drawings.

This invention relates to that class of wire-stretchers which are anchored to the post at one end, and which employ a wire-holder connected to a lever, and dogs which traverse a 15 notched bar.

The improvements are pointed out in the following description and claim.

In the accompanying drawings, forming a 20 part of this specification, Figure 1 is a plan with the post in cross-section; Fig. 2, a side elevation; Fig. 3, a section on line 2 2 in Fig. 1; and Fig. 4 shows, lettered, details enlarged from Fig. 1.

25 Referring to the letters of reference marked on the drawings, B is the ordinary notched bar in such constructions, having the notches e e on each side.

b is an anchor pivotally attached to one end 30 of the bar B for anchoring the device to the fence-post A. The hair-pin-shaped rod C receives the bar B between its two arms. The free ends of the arms of the rod C are pivotally attached at s s to the forked end of the lever D. This forked end of said lever D straddles the notched bar B. The coupling f, which is attached to the bowed end of the hair-pin rod C, is provided with the ordinary eccentric grippers r r for holding the wire u.

40 The dogs a a, which engage the notches e e of the bar B, are pivoted in the ordinary manner on each side of the bar B to the forked end of the lever D.

It is desirable and essential to the practical 45 working of the lever D and dogs a a that the dogs be provided with springs to facilitate the engagement of the dogs with the notches e e. Springs have heretofore been employed in connection with such dogs, but for the above-described purpose only, and in an entirely dif-

ferent relation with the lever D, notches e e, and dogs a a. It is also essential that the fulcrum or pivotal points s s be always kept at the longitudinal center of the notched bar B. An effort has been heretofore made to accomplish this by certain ineffectual and objectionable guides, which need not be herein described. By attaching the springs e e to the lever end of the dogs a a, with said springs between the dogs and the sides of the notched 55 bar B, and bringing the free end of the springs in contact with the sides of the notched bar in a manner to slide over said sides during the operation of stretching the wire, the springs not only perform the ordinary function of actuating the dogs but they also form a yielding 60 guide, allowing the dogs and lever to move freely, and at the same time keeping the pivotal points s s (which points are in fact the fulcrum or axis of the lever D) always at the 65 longitudinal center of the notched bar B.

In the operation, which is similar to that of prior devices, the lever D is swung forward and back, and the ends v of the dogs alternately engage the notches e e on opposite sides. 75

At d, Fig. 1, is shown another eccentric gripper for holding the end of a wire (not here shown) extending past the post from the opposite direction to that shown at u. The use of this, in connection with the wire-holder r r, is 80 to hold the ends of a wire which has been accidentally broken while the ends between the grippers d and r r are spliced or twisted together. By the use of these two grippers or holders slack may be taken out of a wire which 85 has been in use by clamping the wire at d and r r, severing the wire between the grippers, cutting off a piece and splicing the severed ends together. This use is not illustrated, but will be thoroughly understood by wire-fence 90 builders.

We are aware that an anchored notched bar, in connection with the draw-rod and a lever to operate said rod, and carrying spring actuated dogs to engage the notched bar, have 95 been heretofore employed; also, that the anchored bar and draw-rod have been provided with wire-grippers; hence we disclaim invention to such parts *per se*.

Having thus described our improvements, 100

what we claim, and desire to secure by Letters Patent, is—

In a wire-stretcher of the style described, the combination, with the notched bar, hair-
5 pin rod, operating-lever, and dogs, of the dog-springs having free ends forming a sliding contact with the notched sides of the notched

bar to form yielding guides, substantially as set forth.

GEORGE HANN.
ANTON THOMA.
